UNITED STATES PATENT OFFICE.

GUSTAF A. BJORNSON, OF LOS ANGELES, CALIFORNIA.

ROTARY REVERSIBLE ENGINE.

1,118,840.

Specification of Letters Patent.

Patented Nov. 24, 1914.

Application filed September 9, 1913. Serial No. 788,865.

To all whom it may concern:

Be it known that I, GUSTAF A. BJORNSON, a subject of the King of Sweden, residing at Los Angeles, in the county of Los Angeles and State of California, have invented new and useful Improvements in Rotary Reversible Engines, of which the following is a specification.

This invention relates to rotary steam engines, the object in view being to produce an engine of the class referred to which is easily reversible so that it may be caused to operate in either direction desired by the shifting of a single controlling valve.

15 A further object of the invention is to provide a novel construction and combination of rotor and abutment whereby steam pressure is conserved and the steam prevented from leaking around the rotor and 20 abutments and past the sides of both the rotor and abutments.

25 A further object of the invention is to produce a rotary steam engine which is capable of being manufactured at a minimum cost and which may be maintained in working condition economically.

With the above and other objects in view, the invention consists in the construction, combination and arrangement of parts, as 30 will hereinafter be more fully described, illustrated and claimed.

In the accompanying drawings:—Figure 1 is a front elevation of a rotary steam engine embodying the present invention looking toward the gear side. Fig. 2 is also an elevation of the engine looking toward the opposite side. Fig. 3 is a plan view of the same. Fig. 4 is a vertical longitudinal section on the line 4—4 of Fig. 3. Fig. 5 is a 40 diametrical section through the rotor. Fig. 6 is a similar view of one of the rotary abutments. Fig. 7 is a detail cross section on an enlarged scale through the rotor, showing the packing sections applied to one of the 45 piston wings. Fig. 8 is a detail view of the overlapping packing sections. Fig. 9 is an enlarged fragmentary elevation illustrating the relation between the rotor and abutment. Fig. 10 is a detail perspective view of one 50 set of packing sections.

The engine contemplated in this invention comprises a base 1 which is substantially square or rectangular and provided along a medial line with supports 2 for the casing 55 which incloses the rotor and rotary abutments hereinafter particularly described.

The base 1 also supports two series of pillow blocks 3 having bearings 4 for the shafts of the rotor and abutments, 5 designating the shaft of the rotor and 6 the shafts of the rotary abutments arranged in spaced relation to the shaft 5 and equi-distant therefrom at opposite sides.

The casing designated generally by the reference character A comprises three sections, a middle section 7 and two end sections 8 and 9, each of the sections being substantially cylindrical but opening into each other as shown in the vertical longitudinal section, Fig. 4. In the central section 7 is 70 mounted the rotor 10 which as shown is provided with three wings 11 the outer edges of which work in contact with the inner periphery of the sections 7 of the casing, the rotor 10 being of materially less diameter 75 than the internal diameter of the section of the casing in which it works so as to provide the annular steam space or expansion chamber 12.

In the section 8 of the casing is mounted a 80 rotary abutment 13 while a corresponding rotary abutment 14 is mounted in the section 9 of the casing. Each of said rotary abutments is formed with three recesses 15 to receive the wings 11 of the rotor and all 85 of said rotary elements, including the rotor 10 and the abutments 13 and 14 are revolved at exactly the same speed by means of gear wheels 16, 17 and 18 fast on the respective shafts of the rotary abutments and rotor as 90 clearly illustrated in Figs. 1 and 3, the said gear wheels being arranged exteriorly of the casing A.

In order to prevent the leakage of steam around the side faces of the rotor and rotary abutments, the rotor 10 is provided in its opposite faces with annular grooves 19 in which are placed packing rings 20 which work in contact with the opposite side walls of the casing, said casing being shown in the 95 preferred embodiment thereof as closed at one side by a fixed head or side 21 while the opposite side 22 thereof is detachable, being held in place by bolts or cap screws 23. Likewise each of the rotary abutments 13 100 and 14 is provided in its opposite sides with grooves 24 extending between the recesses 15, in which are placed segmental packing sections 25 which work in contact with the inner surfaces of the opposite side walls of 110 the casing A. In this way the steam is prevented from passing around the opposite

sides of the members 10, 13 and 14 thus economizing in the use of steam.

In order to prevent the leakage of steam around the wings 11, each of said wings is formed as shown in the detail section, Fig. 7, wherein it will be observed that each piston wing is provided in the three exposed sides thereof with grooves 26 to receive packing sections 27 and 28. Each of said sections is formed of metal and is of double L-shape so as to embrace the opposite sides of the wing 15 and also extend across the outer face thereof, where said packing sections are oppositely cut away and over-lapped as shown at 29 thus allowing for the necessary expansion and contraction of the packing sections relatively to each other.

At their inner ends the packing sections 27 and 28 are provided with inwardly extending retaining lips 30 which are received in recesses 31 as shown in Fig. 7, the construction referred to limiting the outward movement of the packing sections in a radial direction. Within each of the grooves 25 formed to receive the packing sections 27 and 28 is placed a spring 31' shown as of serpentine form, the springs 31' serving to urge the packing sections outwardly to opposite sides and also toward the inner periphery of the rotor casing, thereby maintaining a close steam-tight contact with the casing and preventing the steam from passing by the piston wings. Stuffing boxes 32 are arranged at opposite sides of the casing 35 to prevent leakage of steam around the shafts 5 and 6 above referred to.

33 designates the steam chest to which steam is led by a supply pipe 34 controlled by a valve 35. Mounted for movement 40 within the steam chest 33 is a slide valve 36 which enables the engine to be reversed as will hereinafter appear. The valve 36 is connected to an operating rod 37 which leads outwardly through a stuffing box 38 45 in the steam chest and is connected to a reversing lever 39 provided with a thumb latch 40 co-operating with a segmental rack 41 extending from the casing A. A single exhaust pipe 42 leads out of the steam chest 50 33 while two sets of steam inlet pipes are used, each set comprising a short pipe 43 and a longer pipe 44, the pipes 44 crossing each other as shown in Fig. 2 and leading 55 into the rotor casing at opposite sides of the rotor 10, the inlet ports of one set of pipes being shown at 45 and 46 in Fig. 4 and the other set of inlet ports being shown at 47 and 48. It will be observed that the ports 45 to 48 inclusive are arranged close 60 to the meeting points of the rotor and rotary abutments so as to leave as little steam space as possible between said ports and the actual points of contact between the rotor and the abutments thus doing away with any steam cushion at such points which

would interfere more or less with the efficiency and power of the engine.

It will be observed that when the valve 36 is moved in one direction it will throw one set of pipes 43 and 44 into operation and when moved in the opposite direction, it will cut off said set of pipes and throw the other set into operation. In this way the steam may be let into the set of ports 45 and 46 or into the other set 47 and 48 with the result that the expansion of the steam will drive the rotor in one direction or the other in accordance with the ports in use.

By reference to Fig. 4 it will be observed that when steam is admitted through the ports 47 and 48, it will act by expansion between the rotary abutments and the piston wings to drive the rotor in a counter-clockwise direction, and when the steam is admitted through the other ports 45 and 46, it will act between the same elements to drive the rotor in a clockwise direction. As the steam is simultaneously expanding against two of the piston wings, the little resistance offered by the steam against the piston wing which is just emerging from the recess 15 in the adjacent abutment will be comparatively slight and will not interfere with the general efficiency of the engine. Furthermore by reason of the particular number and arrangement of the piston wings and recesses in the rotary abutments, the engine cannot stop on a dead center and therefore it will always start as soon as steam is turned into the proper ports.

Oil cups 49 are provided leading through the upper portion of the casing to conduct oil to the rotary abutment and drain cocks 50 are placed at suitable points in the bottom of the casing to turn off any liquid or water or condensation therein.

For use in larger or heavier engines, I prefer to use the form of packing illustrated in Fig. 10 wherein it will be observed that three packing strips 27', 28' and 29 are employed, the peripheral packing section 29 having a dove-tailed terminal engagement with the extremities of the side packing strips 27' and 28' as shown at 29'. The strips 27' and 28' are provided with the unturned retaining lugs 30' having the same function as those shown in Fig. 7.

What is claimed is:—

1. In a rotary steam engine, a casing embodying three cylindrical sections in communication with each other and arranged end to end, rotary abutments journaled in the end sections of the casing and provided with recesses in their peripheries, a rotor journaled in the central section of the casing and embodying piston wings movable into and out of the recesses in the rotary abutments, steam inlets arranged in sets at opposite sides of the rotor and adjacent to the points of convergence of the peripheries

of the rotor and abutments, a steam chest, pipes leading from said chest to said ports, two of said pipes diverging and the other two being crossed, and a manually operable 5 slide valve in said chest controlling all of said pipes.

2. In a rotary steam engine, a casing embodying three cylindrical sections in communication with each other and arranged 10 end to end, rotary abutments journaled in the end sections of the casing and provided with recesses in their peripheries, a rotor journaled in the central section of the casing and embodying piston wings movable 15 into and out of the recesses in the rotary abutments, steam inlets at opposite sides of the rotor and adjacent to the points of con-

vergence of the peripheries of the rotor and abutments, each piston wing being provided with grooves in the exposed faces thereof, 20 overlapping packing sections movably mounted in said grooves and provided with inwardly extending arms having internal retaining lips movable in recesses in the sides of the wing, and springs located behind said 25 packing sections and operating to maintain said sections in contact with the casing.

In testimony whereof I affix my signature in presence of two witnesses.

GUSTAF A. BJORNSON.
